(57) CLAIM

The ornamental design for a weed remover, as shown and described.

DESCRIPTION

FIG. 1 is a perspective view of an embodiment of the weed remover showing my new design;

FIG. 2 is a front plan view thereof;

FIG. 3 is a back plan view thereof;

FIG. 4 is a left-side elevational view thereof;

FIG. 5 is a right-side elevational view thereof;

FIG. 6 is a top plan view thereof;

FIG. 7 is a bottom plan view thereof; and,

FIG. 8 is a right-side elevational view of the weed remover connecting to a tractor.
In the drawings, the broken lines represent environment and form no part of the claimed design.1 Claim, 6 Drawing SheetsFIG. 1

FIG. 2

FIG. 3

FIG. 4

FIG. 5

FIG. 6

FIG. 7

FIG. 8
